(57) **CLAIM**

The ornamental design for a votive candle holder with beaded lamp shade, as shown and described.

DESCRIPTION

FIG. 1 is a perspective view of a votive candle holder with beaded lamp shade of the present invention;

FIG. 2 is a side elevational view of FIG. 1;

FIG. 3 is a top plan view of FIG. 1;

FIG. 4 is a bottom plan view of FIG. 1;

FIG. 5 is a front elevational view of FIG. 1;

FIG. 6 is a rear elevational view of FIG. 1;

FIG. 7 is a perspective view of the votive holder of the present invention;

FIG. 8 is a front elevational view of FIG. 7;

FIG. 9 is a top plan view of FIG. 7;

FIG. 10 is a bottom plan view of FIG. 7;

FIG. 11 is a perspective view of the beaded lamp shade of the present invention;

FIG. 12 is a front elevational view of FIG. 11;

FIG. 13 is a top plan view of FIG. 11; and,

FIG. 14 is a bottom plan view of FIG. 11.
